UNITED STATES PATENT OFFICE.

PHILO E. DANIELS, OF OAKLAND, CALIFORNIA, ASSIGNOR OF ONE-HALF
TO GILBERT P. COATES, OF UNCASVILLE, CONNECTICUT.

CUFF-SUPPORTER.

SPECIFICATION forming part of Letters Patent No. 636,765, dated November 14, 1899.

Application filed April 4, 1899. Serial No. 711,760. (No model.)

To all whom it may concern:

Be it known that I, PHILO E. DANIELS, a citizen of the United States, residing at Oakland, in the county of Alameda and State of California, have invented certain new and useful Improvements in Cuff-Supporters; and I do hereby declare the following to be a full, clear, and exact description of said invention, such as will enable others skilled in the art to 10 which it most nearly appertains to make, use, and practice the same.

This invention relates to improvements in wearing-apparel, and more particularly to cuff-supporters; and it consists of the novel 15 construction and application of the device.

In the drawings, Figure 1 is a perspective view of a cuff and shirt-sleeve, illustrating the application of the supporter. Fig. 2 is a side elevation of the supporter, the sleeve and 20 cuff being shown in section. Fig. 3 is a similar view of the supporter, the parts being in their normal position. Fig. 4 is a plan view of the same.

In the description with reference to the 25 drawings letters of reference will be assigned to the various features of this device.

Structurally the device is composed of an integral strip of spring metal—such as German silver, brass, or the like—the ends being 30 bent backwardly, and upon the opposite sides of the body of the strip forming two oppositely-opening clamps A and B to engage the shirt-sleeve and the cuff, respectively.

In bending the strip C to form the clamps A and B the head A' is first formed on the end of the strip, which is rounded and smoothed to prevent injury to the linen. At approximately one-fourth the length of the strip the 35 bend A² is formed, the extensions of strip from this bend A² being parallel. Just behind the head A' the hump C' is formed in the body C, the portion C^X being formed at an angle to the clamps A and B, which are similar, excepting the direction of their opening.

The above description applies to the manual operation; but it is evident that the operation may be carried out by suitable automatic machinery or dies.

In operation the device is first placed in 50 position on the shirt-sleeve, the clamp A engaging the extremity thereof, as shown in Fig. 2. The position of the device with reference to the cuff is optional with the wearer, the preferred location being that shown in 55 the drawings, Fig. 1—*i. e.*, on the upper side—it being at this point more out of the way and less liable to be seen. If it is desired to show more of the cuff, it may be pulled down without fear of injury, as it slips readily through 60 the clamp A, but is held securely against all ordinary strains. If it is desired to protect the cuffs from being soiled while at work or washing the hands, they may be pushed upward and held in that position, making a 65 perfect adjustment possible.

If it is desired, the device may be made of precious metal or ornamented in various ways. To prevent the metal blackening the linen, the whole may be dipped in a suitable 70 enamel or coated with some substance to prevent this.

Having thus described this invention, it is claimed—

A device of the nature indicated, formed 75 of a piece of resilient material and comprising a body having the oppositely-extending humps therein with the portion C^X extending between said humps, and portions bent backwardly upon the body at opposite ends and 80 on opposite sides thereof, each backwardly-bent portion having its end extending inwardly toward the portion C^X; substantially as described.

In testimony whereof I have hereunto set 85 my hand this 9th day of March, 1899.

PHILO E. DANIELS.
